TRAVELING AGITATOR AND THE LIKE

Arthur L. Whiteside, East Orange, N. J.

Application January 29, 1932, Serial No. 589,568

8 Claims. (Cl. 259—102)

This invention relates to agitators for treating liquid suspensions, such as paper pulp, cement slurries, clays, sewage and the like and more particularly to a traveling agitator which is mounted for movement across a tank containing said suspensions and is adapted for uniform treatment of the various portions thereof. Still more particularly the invention relates to an improved driving mechanism for an agitator of the above type.

10 Among the objects of the present invention are; to provide a light-weight agitating device which occupies a minimum amount of space and which may be operated by a source of power located outside of the tank of material being treated; to provide an agitator which is adjustable as to speed of travel and as to rate and direction of liquid flow; to provide an agitator which may be readily installed and serviced without discharging the tank; to provide an improved driving means whereby positive operation is obtained with minimum power requirements; and to provide an improved, compact and convenient device of the above type.

15 In a preferred form of the invention a propeller is mounted on a vertical shaft and suspended from a traveling carriage in a tank of liquid which it is desired to agitate. The carriage is mounted on a track which extends across the tank in such manner that the carriage is capable of traveling to and fro thereover. For driving the above device a flexible drive, such as a rope, belt, chain or cable is employed which extends across the top of the tank and cooperates with a plurality of operating sheaves mounted on the carriage. The 20 flexible drive may be operated by a suitable source of power, such as an electric motor, which may be mounted outside of the tank. A clutch mechanism is employed and is automatically operated when the carriage approaches the end of its travel to alternately interconnect pairs of said sheaves. Interconnection of certain pairs of sheaves causes movement of the carriage in one direction and interconnection of other pairs of sheaves causes movement of the carriage in the reverse direction.

25 45 The propeller shaft is positively geared to one sheave shaft to provide constant uni-directional agitation during carriage travel and reversal.

The invention will be better understood and further features and advantages thereof will be apparent from the following description which discloses a preferred embodiment thereof taken in connection with the accompanying drawings in which:

55. Fig. 1 is a diagrammatic view of the connection

of the operating sheaves to the flexible driving means;

Fig. 2 is a plan view of the device;

Fig. 3 is a vertical section taken on the line 3—3 of Fig. 2;

Fig. 4 is a vertical section taken on the line 4—4 of Fig. 3;

Fig. 5 is an end elevation of the tank and driving means;

Fig. 6 is a horizontal section taken on the line 6—6 of Fig. 3;

Fig. 7 is a vertical section taken on the line 7—7 of Fig. 6;

Fig. 8 is a vertical section taken on the line 8—8 of Fig. 6;

Fig. 9 is a vertical section taken on the line 9—9 of Fig. 6;

Fig. 10 is a vertical section taken on the line 10—10 of Fig. 6; and

Fig. 11 is a detail of the clutch operating mech- 75 anism.

In the various figures of the drawings like parts have been designated by like reference characters. In the following description and in the claims various details are identified by specific means for convenience but they are intended to be as generic in their application as the art will permit.

Referring to the drawings more in detail, the invention is shown as applied to a tank 10 having end walls 11, side walls 12 and a bottom 13 which is adapted to contain a material, such as paper pulp, cement slurry, clay filler, sewage, etc., which is to be agitated. A plurality of channel beams 14, (Figs. 3 and 4) are carried in end walls 11 and may be attached to floor beams 15, or floor 16 in any convenient manner. Said floor is provided with a manhole 17 of sufficient size to receive the agitating apparatus to be described and to permit the same to be serviced or to be bodily removed from the tank.

The agitating device consists of a carriage formed by transverse frame members 20 and longitudinal frame members 21 which are joined to form a substantially rectangular supporting frame. Said frame is hung from guide wheels 22 which are supported in bearing members 23 carried by uprights 24. Said uprights 24 may be attached to said frame in any convenient manner. A housing 26, adapted to contain the driving mechanism to be described, is formed having suitable dimensions to rest within frame members 20 and 21 and carries lugs 27 by which it is supported on said frame members. Said housing may be attached to frame members 20, 110

and 21 by suitable means, such as bolts 27a. It is to be noted that guide wheels 22 rest within channel beams 14 and are of such size with respect to said channel beams as to roll against the top surface thereof when an upward thrust is exerted by the propeller sufficient to cause vertical lift of the entire apparatus. Said guide wheels normally roll upon the lower surface of the channel beams 14 which serve as a track to guide the carriage in its to and fro travel. It is obvious that the channel beams which support the floor may be utilized for the guide track for the carriage or additional track members may be employed as desired. In any case the track merely serves as a support and a guiding means.

The housing 26 carries a pair of spaced bearing plates 30 and 31 which are mounted horizontally and provide supports for the various shafts and gears to be described. Referring to Figs. 2 and 7, the driving mechanism is shown as comprising coaxial sheaves 32 and 33 and additional sheaves 34 and 35.

Sheave 32 is keyed to shaft 36 which is supported in suitable bearings 37 and 38 in bearing plates 31 and 30, respectively, and at its lower end is provided with a gear 39 which is rigidly secured thereto. A suitable thrust bearing, such as collar 40, may be employed to maintain the correct operating position of said shaft.

Sheave 33 is secured to a sleeve 41 which is freely rotatable on shaft 36 and carries a gear 42 rigidly secured thereto. Gear 42 is constantly in mesh with a cooperating gear 45, rigidly secured to a shaft 46, which is mounted in suitable bearings 47 and 48 in bearing plates 31 and 30 respectively. Gear 39 meshes with a cooperating gear 49 which is loosely mounted on shaft 46 and is free to rotate thereabout.

Shaft 46 is extended through housing 26 and carries a propeller which may be secured thereto by any suitable means as by nut 46a and preferably is provided with blades 50 which are adjustable about their own axes whereby the pitch of the propeller may be varied as desired. Suitable means, such as set screws 50a, may be provided for locking blades 50 in position. A three blade propeller is particularly suitable inasmuch as it may be more readily removed through man-hole 17 which may be of slightly smaller dimensions than the over-all dimensions of the propeller. A housing 46b may be secured to housing 26 and is adapted to enclose shaft 46 and to provide a lower bearing therefor. Bracing rods 51 extending between housing 26 and collar 52 on housing 46b impart rigidity to the propeller shaft 46 and prevent undesired vibration thereof.

Referring to Figs. 2, 6 and 7, it will be noted that gear 45 meshes with a cooperating gear 55 which is keyed to shaft 56. Said shaft 56 is mounted in bearings 57 and 58 and carries gear 59 in spaced relationship to gear 55. Said gear 59 is in mesh with a gear 60 which is mounted for free rotation about shaft 61. Said gear 60 is provided with a lug 62 (Fig. 10) by which driving force is applied in a manner to be described. Shaft 61 carries sheave 34 rigidly attached thereto, and is supported in suitable bearings 63 and 64 in said bearing plates 31 and 30 respectively. A collar 65 is keyed to shaft 61 and carries a yoke 66 (Fig. 6) in which a latch member 67 is pivoted as by rod 68 (Figs. 6 and 10). Said latch member 67, in the position shown in Fig. 10, engages lug 62 and establishes a driving connection between shaft 61 and gear 60. It will be

noted that the above described mechanism establishes a driving connection between sheaves 33 and 34 and that latch member 67 forms a clutch for selectively interrupting the driving connection and permitting sheaves 33 and 34 to rotate as idlers.

Referring to Figs. 6 and 8, it will be noted that a driving connection is established between sheaves 32 and 35 by means of gear 49 which rotates independently of shaft 46 and meshes with a gear 70 which is keyed or otherwise secured to shaft 71. Said shaft is mounted in plates 31 and 30 by means of bearings 72 and 73 respectively. Gear 70 meshes with a gear 75 which is loosely mounted on shaft 76. Said shaft 76 carries sheave 35 and is supported in plates 31 and 30 by bearings 77 and 78 respectively. A collar 79 is rigidly secured to shaft 76 and carries a yoke 80 (Figs. 6 and 10), in which latch member 81 is pivoted as by rod 82. Said latch member 81 cooperates with a lug 83 which is carried by gear 75 and, when in engaging position, establishes the driving connection between sheaves 32 and 35. When latch member 81 is disengaged sheaves 32 and 35 are free to rotate as idlers.

For selectively operating the clutch mechanism formed by latches 67 and 81 and lugs 62 and 83 respectively, collars 88 and 89 are provided which are slidably mounted on shafts 61 and 76 respectively. Collar 88 is provided with a pair of flanges 90 and 91 which cooperate with arm 92 formed on latch member 67 to control the position of said latch member. Collar 89 is provided with a similar pair of flanges 95 and 96 which cooperate with arm 97 formed on latch member 81 for controlling the position thereof.

For operating collars 88 and 89 a lever 100 is provided which is carried by rod 110. Said rod is pivoted in a bracket 101 which is supported by bearing plate 31 in any convenient manner. Said lever 100 carries at one end a member 102 which cooperates with flanges 90 and 104 formed on collar 88 for controlling the position of said collar. At its other end lever 100 carries a member 105 which cooperates with flanges 95 and 106 of collar 89. It will be noted that with the lever in the position shown in Fig. 10 latch 67 is brought into engagement with lug 62 for establishing a driving connection between sheaves 33 and 34 and latch 81 is raised out of engagement with lug 83 whereby sheaves 32 and 35 are disconnected from each other and are free to operate as idler sheaves. With lever 100 in the opposite position the connections will be reversed whereby a driving connection is established between sheaves 32 and 35 and sheaves 33 and 34 are permitted to operate as idler sheaves. With the lever in a central position both latches are disengaged from their respective lugs and no driving connection exists between either sheaves 32 and 35 or 33 and 34, all of said sheaves being free to revolve as independent idlers.

Rod 110 is provided with a downwardly extending section 111 which is pivoted to rod 112 (Figs. 6, 9 and 10). Rod 112 is pivoted to a bell crank lever 113 which is in turn connected by a rod 114 to lever 115. Lever 115 is provided with a hub member 116 which is mounted for pivotal movement about shaft 117. Said hub member also carries an ear 118 to which a pin 119 is secured, engaging a spring 120 which is anchored between said pin 119 and a stationary eye 122 secured to bearing plate 30. A suitable yoke 125 is also secured to said plate and carries rod 117. Lever 111 may be locked in neutral position by 150

any convenient device, such as forked member 111a which is secured to the housing and, when in engaging position, centers and locks said lever. The carriage is then free to move along the tank 5 and may be manually positioned, for example, under the manhole 17 or may be manually operated in case of failure of the driving mechanism.

A segmental gear 126 is mounted on rod 117 and cooperates with a rack 127. Spring 128 is 10 connected to gear 126 and is anchored to a suitable post 130 in bearing plate 30. Gear 126 carries a pair of pins 126a which extend outwardly therefrom and engage lever 115. Gear 126, however, is free to move independently of said lever 15 within the limits defined by the distance between pins 126a.

Spring 128 is adapted normally to hold gear 126 in either of its extreme positions without interfering with free movement of said gear in 20 response to movement of rack 127. When said gear has moved a sufficient distance to cause one of said pins 126a to contact with lever 115 and to move said lever past its central position, spring 120 will cause lever 115 to move rapidly to its 25 other extreme position. The lost motion provided by pins 126a and lever 115 accordingly permits a quick action of lever 115 and the operating mechanism associated therewith whereby the clutch mechanism is quickly thrown from one position 30 to the other when movement of rack 127 takes place.

Referring to Fig. 9 it is noted that rack 127 is carried by rod 135 which is slidably mounted in bearings 136 in housing 26. Said rod extends beyond 35 said housing on both ends thereof and engages stop members 137 and 138 which are mounted on the two ends 11 of tank 10. The arrangement is such that when the carriage approaches either end of tank 10, rod 135 engages the corresponding stop member and causes movement of 40 rack 127, thereby throwing lever 117 and, through the linkage above described, reversing the position of latch members 67 and 81.

The driving means for the above described 45 mechanism comprises a flexible driving member 140, such as a belt, chain, rope or cable which for ease of description will be hereinafter referred to as a rope passing around sheaves 32, 33, 34 and 35 in a manner to be presently described. At one 50 end of tank 10 said rope is passed around idler sheave 141 which is mounted on end wall 11 in any convenient manner. Said rope extends across the top of tank 10 and passes around idler sheaves 142 and 143 (Figs. 3 and 5), and thence 55 around driving sheave 145. Said driving sheave and an intermediate sheave 146 which is rigidly secured thereto are mounted on a sleeve 146a to revolve freely on shaft 147 in arms 148 which are pivotally supported from a stationary supporting member 149. A tensioning means, such as 60 weight 150 may be hung as by yoke 151, from rod 147 and is adapted to maintain proper tension on the driving rope 140.

Sheave 146 is driven by belt 152 from sheave 65 153. Said sheave 153 is rigidly secured to a sheave 154 which is mounted for rotation in supporting member 149. For mounting arms 148 and sheaves 153 and 154, a rod 155 may be employed which extends between bearings 156 carried by said supporting member 149. A suitable driving motor 70 157 is coupled to sheave 154 as by belt 158. Obviously other driving means such as silent chains or flat belts may be substituted for belts 152 and 158. The above arrangement is such that limited 75 movement of sheave 145 may take place to main-

tain the proper tension on rope 140 without altering the tension of belts 152 and 158 and consequently without changing the driving force which is transmitted from motor 157 to said sheave 145.

Referring to Figs. 2 and 3, it will be noted that 80 rope 140 passes from driving sheave 145, around sheave 142 thence around sheaves 35, 33, idler sheave 141 and sheaves 32 and 34 in the order named; thence around idler sheave 143 and back to the driving sheave 145. Wall 11 may have a 85 slot 160 (Fig. 5) formed therein to receive rope 140 so that an endless rope may be inserted around the various sheaves above mentioned. One arm 148 and yoke 151 may be readily removable in order to permit said endless rope to be 90 applied to sheave 145.

Inasmuch as the rope 140 passes from an upper sheave 32, around to idler sheave 141, to a lower sheave 33, it is obvious that said sheave 141 may be mounted in an inclined position or may be formed with a wide groove to permit the necessary lateral movement of the rope to take place. 95

A suitable cover 165 may be mounted over the 100 entire operating mechanism and may rest upon housing 26 and be secured thereto in any convenient manner. Slots 166 may be formed in cover 165 to permit the same to pass over rope 140. Said cover is adapted to be lowered through manhole 17 and it is to be noted that the operating mechanism including the various sheaves are 105 accessible through said manhole and the rope may be threaded about said sheaves while the apparatus is located under the manhole in the position shown in Fig. 3. The apparatus, however, is entirely carried within the tank and does not 110 extend above the floor or require space, other than that within the tank itself. Furthermore, the apparatus may be constructed of comparatively light material inasmuch as it is driven by rope 140 in the manner to be pointed out and 115 does not depend upon the traction of wheels 22 for the driving force. Said wheels in the present invention merely serve as guide means and contact with either the lower or upper surfaces of 120 channels 14 depending upon the direction and amount of thrust exerted by the propeller.

In the above described apparatus sheaves 32 and 35 and sheaves 33 and 34 are shown as of 125 different diameters and the driving connection between the pairs of gears in such that when either of said pairs is coupled by the above described clutch mechanism, a one to one gear ratio is established and the gears drive at identical speeds. For this reason it will be noted that the two sheaves of the coupled pairs, of unequal diameters, for example sheaves 32 and 35, travel at different peripheral speeds. This feature is made use of in a manner to be described for causing the lateral movement of the carriage. It will be obvious, however, that the different peripheral 130 speeds of the coupled sheaves can be obtained by various other means, as for example by constructing the sheaves of the same diameter and so constructing the gears that they are caused to rotate at different angular speeds. 135

When a moving rope passes over a sheave that is free to move laterally and the sheave is forced to revolve at a peripheral speed different from that of the rope the sheave will rotate and in addition, will move laterally in the direction of travel 145 of the rope or in the reverse direction depending upon whether the peripheral speed of the sheave is less or greater, respectively than the speed of travel of the rope. In either case the speed of lateral movement of the sheave will be equal to 150

the difference between its peripheral speed and the speed of travel of the rope.

Referring to the diagram of Fig. 1, it may be assumed that sheaves 33 and 34 are coupled for the same angular speed of rotation and sheaves 32 and 35 are free to rotate as idlers. Assuming, by way of example, that the ratio of the diameter of sheaves 33 and 34 is such that sheave 33 has a peripheral speed of 1300 feet per minute and sheave 34 has a peripheral speed of 1100 feet per minute and that rope 140 has a forward speed of 1200 feet per minute, it will be noted that sheave 33, which has a speed greater than that of the rope will tend to move in the direction opposite to that of the rope or to the left as viewed in Fig. 1. Sheave 34, having a speed less than that of rope 140, will tend to move in the direction of movement of the rope or to the left as shown in Fig. 1. The rate of lateral movement of both of said sheaves will be 100 feet per minute in the example above given and the carriage will accordingly be caused to move laterally across tank 10 at that speed.

When the clutch mechanism is operated by rod 135 engaging abutment 138 at the left hand end of the tank, sheaves 33 and 34 are disconnected and are permitted to operate as idlers and sheaves 32 and 35 are coupled. Said sheaves 32 and 35 both tend to move to the right as shown in Fig. 1 for reasons similar to those outlined above. Reverse movement of the carriage accordingly takes place which will continue until rod 135 contacts with abutment 137 and again operates the clutch mechanism. To and fro movement of said carriage accordingly takes place so long as power is applied to rope 140 or until lever 111 is locked in neutral position. The propeller, which is operated by shaft 46 to which power is continuously applied from sheave 33, is continuously operated regardless of the movement of the carriage.

Since the power required for operating the propeller is greatly in excess of that required for causing lateral movement of the carriage, the shock on the driving motor occasioned by reversal of the movement of the carriage is negligible. Furthermore, by reason of the substantially constant power requirements and the elimination of the necessity of a heavy starting torque, a motor of comparatively small power may be employed.

In a preferred form of the invention a fume proof transmission rope is employed which may be readily removed and replaced in the manner above described and which may be readily disconnected from the driving sheaves when it is desired to remove the apparatus from the tank. Furthermore, by locating the source of power at a point outside of the tank, the space requirements are minimized and also the weight of the carriage is reduced and the necessity for shielding the motor from fumes is avoided. The entire device may be enclosed in a substantially splash proof cover and a completely sealed housing and both may be formed of fume proof material or the unit may be protected by a metal coating or paint as may be required. The term sheave has been used herein for convenience but it is intended to include various types of rotating members capable of cooperating with the belt, chain, cable, rope or other type of flexible drive.

The device may be operated in a place having low head room inasmuch as a carriage of minimum thickness is employed and the gear box, if desired, can be sealed and actually run within the

mixture. The maximum height of the mixture in that case would be just below the rope 140.

It is to be noted that motors, trolleys, trolley wires, exposed wheel drives, control switches and all moving parts liable to be affected by vapors or fumes have been eliminated or removed to a location without the tank.

The complete operating unit is readily accessible through the manhole which is preferably of a size such that the gear box may be passed therethrough for installation. For servicing the sheaves, the gear box cover is readily removed and the rope may be removed from the sheaves without unsplicing so that the complete unit may be detached from the carriage frame when necessary.

A feature of the invention resides in the fact that maintenance and servicing may be accomplished without emptying the tank and that replacement units can be installed with a minimum of interruption and delay.

The continuous propeller action produces a flow of liquid in one direction, that is, a vertical flow either upwardly or downwardly. The propeller blades, being adjustable, can be set for any desired velocity of flow, either upwardly or downwardly. This feature is important in certain instances, as for example in treating cement slurry which may require an upward flow to carry heavy precipitating particles into the upper strata and in treating other mixtures, such as pulps which may require a downward flow of liquid to bring the floating materials or light density liquids into thorough intermixture at the bottom.

By reason of the elimination of the shock load which would otherwise occur on carriage reversal, a small motor without high torque characteristics and without electrical controls, other than a starting switch, may be employed.

The velocity of flow through the propeller, and the frequency of passing the propeller through any area may both be independently adjusted to suit the consistency and precipitating characteristic of the mixture or solution to be agitated.

The speed of travel of the carriage may be varied by changing the gear ratios or the sheave diameters or by changing the motor speed. The velocity and direction of flow of liquid may be controlled by varying the angle of the propeller blades or by changing the motor speed or the diameter of sheave 33 or gear ratio of the gear train interconnecting shaft 46 and sheave 33.

In the above description a single propeller has been shown by way of example. It is evident however that a plurality of propellers, either on the same or different shafts may be employed, or a plurality of traveling carriages may be mounted over a single tank on the same or separate tracks and driven by one or a plurality of ropes.

Although a specific embodiment of the invention has been described for purposes of illustration, various modifications and alterations will be apparent to a person skilled in the art to which it appertains and the invention is only to be limited in accordance with the scope of the following claims.

What I claim is:

1. An agitator comprising a carriage having a rotatable member, a flexible driving means peripherally engaging said member, means cooperating with said driving means for causing said member to rotate at a peripheral speed differing from the linear speed of said driving means where-

- 5 by lateral movement of said member takes place, pulleys mounted for rotation about fixed axes located beyond the opposite ends of the path of lateral movement of said member, said flexible driving means engaging said pulleys, an agitating device mounted on said carriage, and means whereby rotation of said member operates said agitating device.

10 2. In combination, a carriage mounted for lateral movement, said carriage having a plurality of rotatable members thereon, means for coupling certain of said members and causing the same to operate at different peripheral speeds, a flexible driving means peripherally engaging said members and traveling at a linear speed intermediate the peripheral speeds of said members whereby lateral movement of said carriage is thereby effected, and pulleys mounted for rotation about fixed axes beyond the opposite ends of the path of movement of said carriage, said flexible driving means engaging said pulleys.

15 3. In combination with a carriage, a plurality of rotatable members mounted thereon, a flexible driving means peripherally engaging said members, selective means for causing certain of said members to rotate at a peripheral speed different from the linear speed of said driving means, utilizing the speed differential to produce lateral movement of said carriage in one direction and selective means for causing others of said members to rotate at other differential speeds with respect to the linear speed of said driving member to produce movement of said carriage in the opposite direction.

20 4. A carriage having two pairs of rotatable members, each of said pairs having means for establishing a driving connection therebetween, such that the members of each pair rotate at different peripheral speeds, a flexible driving means peripherally engaging said members and means for alternately interconnecting the members of each pair and causing the members of the other pair to operate as idlers, the relationship between the linear speed of travel of said driving means and the peripheral speed of the said members being such that lateral movement of said carriage is effected.

25 5. An agitating device for a tank comprising a carriage mounted for movement across said tank, a propeller carried thereby and extending within said tank, said carriage having a plurality of rotatable members thereon mechanically arranged in pairs, a clutch mechanism for selectively interconnecting the members of each pair, a flexible driving member peripherally engaging said members, the members of each pair being rotated at peripheral speeds differing from the linear speed of travel of said driving member when said members are mechanically interconnected and means mounted on said carriage and operated when said carriage approaches the end of its travel for controlling said clutches and thereby causing reversal of movement of said carriage.

30 6. In combination with a tank, an agitating device comprising a carriage, means for mounting said carriage for movement across said tank, a propeller carried by said carriage and extending within said tank, a flexible driving member extending parallel to the line of movement of said carriage, rotatable members carried by said carriage and peripherally engaging said driving member for obtaining driving force therefrom, clutch mechanism for selectively controlling the direction of said driving force and operating means for said clutch mechanism comprising a 35 100 105 110 115 120 125 130 135
